Inventor
Frank Macy

UNITED STATES PATENT OFFICE.

FRANK MACY, OF CONVERSE, INDIANA.

SERVING DISH.

Application filed January 2, 1925. Serial No. 266.

This invention relates to what may be termed, an improved serving dish for ice cream, fruit, food and the like and the object thereof is to provide a dish into which 5 may be quickly inserted, a cheap serviceable lining of water proof paper which, after being once used, may be quickly discarded.

Another object is to provide a serving dish as described above, for use in connection with an apparatus for inserting a paper lining in said dish.

With the foregoing and other objects in view which will appear as the description proceeds, the invention resides in the combination and arrangement of parts and in the details of construction hereinafter described and claimed, it being understood that changes in the precise embodiment of the invention herein disclosed may be made 20 within the scope of what is claimed without departing from the spirit of the invention.

In the accompanying drawings:—

Figure 1 represents a perspective view of the serving dish with a lining mounted 25 therein and partially broken out.

Figure 2 is a detail bottom plan view of one corner of the serving dish illustrating the means for receiving and holding the paper lining in the dish.

Figure 3 is a detail sectional view 30 through one portion of the serving dish.

Figure 4 is a view of the forming block which inserts the paper lining in the dish and which is a part of the apparatus for inserting said lining, and the entire Figure 4 is shown here only to illustrate the operation of the dish.

In the embodiment illustrated the serving dish 1 which is designed to be lined by an apparatus for use in connection therewith comprises a food receiving body 2 here shown rectangular in configuration and having flared side walls or flanges 3 and removable end walls 3^a which are also flared. 45 The corners of this dish have slots as shown at 9 and the slots extend longitudinally along the faces of the side members as shown at 10 to allow the rim or flanges 3 to spring out slightly at these points when the paper lining is crowded out through the openings 9, by fins on a forming block which operates in the apparatus for applying the paper linings, thus preventing a rupture of the paper lining which might otherwise occur.

Apertured ears 4 depend from opposite

sides of the dish 1 and are designed to support a rod 5 which extends transversely across the bottom of said dish and has mounted thereon a coiled spring 6 designed 60 to engage the rods 8 which carry the ends 3^a of the dish 1, said ends being movable toward and away from the body of the dish by means of hand grips 7. By moving said hand grips 7 toward each other against the 65 tension of the spring 6 which movement releases the lining shown at L Fig. 1 and permits it to be thrown out of the dish after having been used.

In the use of this dish, it is mounted in 70 the apparatus for inserting the lining and in which the paper for such lining is suspended over the top of the dish and is applied by a descending forming block which causes the paper to conform to the shape of 75 the dish while the surplus paper of the upturned lining is crowded out through the openings 9 by metal fins 12 on the corners of the forming block 11 shown by Fig. 4, the paper being pinched in the openings 9 by 80 pressure of the end members 3^a actuated by the spring 6 through medium of the rods 8, the lining being thus securely held while the forming block and fins are withdrawn and until it is discarded by closing the hand 85 grips 7, which also serve as legs for the dish.

The paper used for lining the dish is formed in tight rolls and inclosed in a housing in the apparatus which inserts the lining and is protected against atmospheric 90 conditions. It is never touched by the hand or any serving instrument, thus insuring its being retained in a sanitary condition.

I claim:—

1. A serving dish comprising a substantially rectangular body member having flared side walls, flaring end members mounted to close the ends of said dish, spring means for holding said ends in closed position and means for moving said ends 100 away from the dish when it is desired to release them.

2. A dish for shaping a flat paper blank and holding it in dish form, which includes a body having upstanding sides and open ends, and means movably connected to the body for closing said ends thereby to crimp and grip portions of the blank between the meeting edges of the sides and the end closing means.

3. A dish for shaping a flat paper blank and holding it in dish form, which includes

2
a body having upstanding sides and open ends, end walls, yielding means for pressing said end walls to position across the open ends of the body, thereby to crimp and grip portions of the blank between the meeting edges of the sides and end walls.

4. A dish for shaping a flat paper blank and holding it in dish form, which includes a body having upstanding sides and open ends, end walls, yielding means for press-

ing said end walls to position across the open ends of the body, thereby to crimp and grip portions of the blank between the meeting edges of the sides and end walls, and means for shifting the end walls to release 15 the gripped portions of the blank.

In testimony that I claim the foregoing as my own, I have hereunto affixed my signature.

FRANK MACY.
